UNITED STATES PATENT OFFICE

JOEL E. PRIESTER, OF HARRISBURG, TEXAS.

ALARM DEVICE.

1,110,713.

Specification of Letters Patent. Patented Sept. 15, 1914.

Application filed February 10, 1914. Serial No. 817,898.

To all whom it may concern:

Be it known that I, JOEL E. PRIESTER, a citizen of the United States, residing at Harrisburg, in the county of Harris and State 5 of Texas, have invented certain new and useful Improvements in Alarm Devices, of which the following is a specification.

This invention relates to new and useful improvements in an alarm device.

10 The object of the invention is to provide a device of the character described to be used in connection with a boiler and operatively connected with the steam whistle, whereby when the water falls below a certain level in the boiler the mechanism will 15 automatically operate to blow the whistle.

With the above and other objects in view, the invention has particular relation to certain novel features of construction, operation and arrangement of parts, an example 20 of which is given in this specification and illustrated in the accompanying drawings, wherein—

Figure 1 is a side elevation of the device 25 attached to the boiler and operatively connected to the whistle, and Figs. 2 to 9, inclusive, show detail views of separate parts of the device.

Referring now more particularly to the drawings, the numeral 1 indicates the boiler 30 having the usual steam dome 2, from which the steam pipe 3 leads. This pipe carries the steam whistle 4, of the usual and well known construction. The numeral 5 refers 35 to a section of pipe, whose lower end has the elbow 6, which is inwardly turned and tapped through the side of the boiler below the normal water level and communicates with the interior of the boiler. The 40 upper end of the pipe 5 is closed by means of the cap 7, from which a short rigid arm 8 extends laterally. The numeral 9 refers to a spherical weight, which is slidably mounted on the lower end of the pipe 5, 45 so as to have a vertical movement on said pipe. Fixed to the pipe 5, above said weight is a hinge member 10, to which one end of the link 11 is pivoted. A rod 12 is adjustably secured at its upper end to the free end 50 of the arm 8 and the lower end of said rod is pivoted to the outer end of link 11. De-

pending from the outer end of said link and integral therewith is an arm 13, whose lower end has the hook 14. Extending upwardly from the weight 9 is the neck 15, 55 whose upper end has an annular flange 16 and the hook 14 is provided to engage under said flange and hold the weight 9 elevated. A cable 17 is attached at its lower end to the weight 9 and at its upper end to the lever of the whistle 4.

When the water in the boiler 1 falls below the orifice through which the elbow 6 is tapped into the interior of said boiler, steam is permitted to enter and pass through 65 the elbow 6 into the pipe 5 and this steam being hot heats the pipe 5 and causes the same to lengthen, as indicated by dotted lines in Fig. 1, in accordance with a well known physical law. As the pipe 5 lengthens an upward pull is exerted on the rod 12 through the arm 8 and the outer end of the link 11 is therebey elevated, causing the lower end of the arm 13 and the hook 14 to swing outwardly from the pipe 5, thus 70 disengaging said hook from under the flange 16 and permitting the weight 9 to drop to the position indicated by dotted lines in Fig. 1. A downward pull is thus exerted on the cable 17 and the whistle lever lowered, causing the whistle to blow in the well known manner. Alarm is thus given, indicating that the water in the boiler is below 75 the normal level.

What I claim is:—

85 In a device of the character described, the combination with a boiler, of a steam line leading therefrom, a steam whistle carried by said line, a hollow pipe whose lower end is inwardly turned and tapped into the wall 90 of said boiler, a closure for the upper end of said pipe, an arm integral with and extending laterally from said closure, a spherical weight slidably mounted upon said pipe, and having an annular flange upon 95 its upper side, a cord one end of which is attached to said weight, and the other end of which is attached to the whistle lever, a rod whose upper end is adjustably secured 100 to the free end of said arm, a hinge member adjustably secured on said pipe, a link, one end of which is pivoted to the lower end of

said rod and the other end of which is pivoted to said hinge member and a hook integral with and depending from said link and whose free end engages under said 5 flange and normally holds the weight in an elevated position.

In testimony whereof I have signed my

name to this specification in the presence of two subscribing witnesses.

JOEL E. PRIESTER.
